SPRING SASH BALANCE

Peter A. Lustig, Detroit, Mich., assignor to Star Products Company, Detroit, Mich., a corporation of Michigan

Application May 3, 1946, Serial No. 667,135

1 Claim. (Cl. 16—198)

1 This invention relates to sash balancing devices and in particular to spring-actuated sash balances.

One object of this invention is to provide an improved spring sash balance having the spring completely enclosed within the spring drum, thereby protecting the spring and also providing bearing surfaces for the drum at the opposite ends thereof.

Another object is to provide a spring sash balance as set forth in the preceding object, wherein the spring drum comprises two interfitting cup-shaped members enclosing the spring and preferably having integral struck-up portions for anchoring the end of the spring.

Another object is to provide a spring sash balance as set forth in the preceding objects wherein improved means is provided for attaching the end of the tape to the drum.

Another object is to provide a spring sash balance as set forth in the preceding objects wherein the two halves of the spring drum are united by a tab engaging a slot in the interfitting flanges of the drum halves.

Another object is to provide a spring sash balance having a spring drum rotatably mounted in a casing of improved design, the parts of which are easily adapted to mass production and assembly.

Another object is to provide a spring sash balance as set forth in the object immediately preceding, wherein the casing includes a construction adapted to be secured to any one of a variety of sizes and shapes of attachment plates without making any changes in the casing or drum.

Other objects and advantages of the invention will become apparent during the course of the following description of the accompanying drawings, wherein:

Figure 1 is a cross section through an upper corner of a window frame showing a side elevation, partly in section, of a sash balance according to a preferred embodiment of the invention;

Figure 2 is an approximately horizontal section along the broken line 2—2 in Figure 1;

Figure 3 is a vertical section along the line 3—3 in Figure 1;

Figure 4 is a left-hand elevational view of the spring drum mounted inside the spring sash balance in Figure 1;

Figure 5 is a perspective view of one of the casing halves employed in the sash balance of Figure 1;

Figure 6 is a perspective view of the other casing half interfitting with the casing half shown in Figure 5;

2 Figure 7 is a perspective view of a mounting plate or face plate used in the spring sash balance of Figure 1;

Figure 8 is a front elevation of the outer spring drum half used in the spring sash balance of Figure 1;

Figure 9 is a right-hand side elevation of a portion of Figure 8;

Figure 10 is a front elevation of the inner spring drum half fitted into the corresponding half shown in Figure 8;

Figure 11 is a left-hand side elevation of a portion of Figure 10;

Figure 12 is a perspective view of the axle used in the sash balance of Figure 1, and;

Figure 13 is a cross-section along the line 13—13 in Figure 1.

Referring to the drawings in detail, Figure 1 shows a preferred embodiment of the spring sash balance of the invention, generally designated 10, as mounted in an upper corner of a window frame, generally designated 11 having side members 12 (one only being shown) and a top cross member 13. The side member 12 is provided with a recess 14 for receiving the end of the cross member 13 and the latter is also provided with an aperture 15 through which the sash balance 10 is inserted and secured.

The sash balance 10 is provided with a casing generally designated 16, composed of interfitting halves 17 and 18 to which a mounting plate or face plate 19 is secured (Figures 5, 6 and 7). The casing half 17 consists of a side plate 20 having a partially semi-circular edge 21 and tabs 22 bent inwardly at intervals along the edge 21. Arcuate slots 23 in a circular pattern are formed in the side plates 21. Integral with the side plate 20 and bent approximately at right angles thereto is a bottom plate 24 having an elongated rectangular aperture 25 therethrough near the end 26 thereof and an approximately rectangular notch 27 in the opposite end 28. The bottom plate 24 is slightly shorter than the side plate 20 so that the ends 26 and 28 are inset from the edge 21 by approximately the thickness of the casing half 18 so as to provide a flush joint therebetween when the halves 17 and 18 are assembled.

The casing half 18 consists of a side plate 29 having an outline corresponding to the outline of the side plate 20. The side plate 29 is provided with arcuate slots 30 disposed in a circular path corresponding to and immediately opposite the arcuate slots 23 in the side plate 20. The casing half 18 is also provided with an edge flange 31 bent substantially at right angles to the side plate 29 and of outline slightly smaller in size

than the outline of the edge 21 so as to fit into the space inside the tabs 22 when the halves 17 and 18 are assembled.

The mounting plate or face plate 19 consists of an approximately rectangular plate 32 having a semi-circular end 33 with a countersunk conical portion 34 therein having a hole 35 for receiving a fastener 36 (Figure 1). Near the opposite end 37, the plate 32 is provided with an approximately rectangular portion 38 struck-up approximately at right angles to the plate 32 and leaving a rectangular aperture 39 therein. Intermediate the ends 33 and 37, the plate 32 is provided with a second struck-up portion 40, also of approximately rectangular outline, but inclined relatively to the plate 32 and leaving an approximately rectangular aperture or recess 41 therein.

The casing halves 17 and 18 in assembly are also interconnected by a tubular axle 42 (Figure 12) formed of a single piece of sheet material, such as sheet metal, bent into a cylinder with its opposite edges 43 and 44 spaced apart from one another by a slight gap. The opposite ends 45 and 46 are provided with integral projecting tabs 47 and 48 respectively spaced in the same relationship to enter the arcuate slots 30 and 23 in the casing halves 18 and 17 respectively.

Rotatably mounted upon the axle 42 inside the casing 16 is an approximately cylindrical spring drum 50 composed of interfitting or mating cup-shaped halves 51 and 52 (Figures 8 to 11 inclusive). The outer drum half 51 consists of a side plate or end 53 having a central bore 54 therein for receiving the axle 42 and also having an edge flange 55 bent approximately at right angles to the side plate 53. The side plate 53, surrounding the bore 54, is struck outwardly to provide an annular boss 56 for spacing the side plate 53 slightly inwardly of the side plate 20 of the casing half 17 (Figure 3). A rectangular notch 57 is provided in an edge of the flange 55. An inwardly struck tab 58 is formed in the flange 55, leaving an approximately rectangular opening 59.

The corresponding or inner drum half 52 (Figures 10 and 11) is similarly provided with an edge flange 60 of slightly smaller diameter than the edge flange 55 so as to nest therein. A similar bore 61 is provided, surrounding by a similar boss 62 for the same purpose as the boss 56. The edge flange 60 is provided with a pair of spaced rectangular apertures 63 and 64, the former being of a size corresponding with and adapted to receive the tab 58 when the two halves 51 and 52 are nested (Figures 1 and 13). This construction prevents relative rotation between the drum halves 51 and 52.

The flange 60 is also provided with an inwardly struck tab 65 leaving an aperture 66 of approximately rectangular outline, the tab 65 being provided as an anchorage for the outer end 67 of a spiral spring 68, the latter being bent relatively to the former around the edge of the tab 65 (Figure 1). The inner end 69 of the spiral spring 68 is likewise bent so as to enter the gap between the axle edges 43 and 44 (Figure 12). The sash balance 10 is likewise provided with a flexible connecting member 70 (Figure 1) such as a steel tape having its lower end 71 engaged by a U-shaped member 72, the middle of which encircles a ring or rectangular loop 73 which is attached to the upper edge of the window sash and the ends of which are secured to the end 71 of the tape 70, as by welding. The inner end 75

74 of the tape 70 (Figure 1) is connected to the drum 50 as described below.

In the assembly of the sash balance of this invention, the drum halves 51 and 52 are nested by pushing the latter within the former (Figures 8 and 10) until the tab 58 snaps into the aperture 63 (Figures 4 and 13). The end 74 of the connecting member or tape 70 is then threaded inwardly through the aperture 66 and bent at that point, then threaded outwardly through the aperture 64 with its tip overlying the portion 75 of the edge flange 55 lying between the aperture 57 and the aperture 59, with the result shown in Figure 1. The tape 70 is then wound upon the drum 50 in the manner shown in Figures 1 and 4.

Meanwhile, the bottom plate 24 of the casing half 17 is secured to the face plate or mounting plate 19 in any suitable way as by spot welding at any convenient locations such as the points 76 (Figure 5). During welding, the struck-up portion 40 serves as a locating member by engaging the outer edge of the aperture 25, and the struck-up portion 38 projects upwardly through the notch 27.

The axle 42 is then inserted through the holes 54 and 61 in the drum halves 51 and 52, and its tabs 48 inserted through the holes 23 in the casing half 17. The casing half 18 is then brought together over the drum 50 and casing half 17 so as to enclose them, and at the same time, the tabs 47 on the exposed end of the axle 42 are inserted through the slots 30. When the casing 16 is thus completely assembled, and the end 71 of the tape 70 has been passed through the apertures 27 and 39, the tabs 47 and 48 are turned over (Figures 1 and 3) and recessed into the side plates 20 and 29 so as to be flush therewith and thus anchor the assembly together. It will be evident from Figure 3 that the clinching of the axle tabs 47 and 48 against the side plates 20 and 29 in this manner at the same time brings the outer surfaces of the annular bosses 56 and 62 into frictional engagement with the inner surfaces of the side plates 20 and 29 respectively, thus setting up a frictional drag therebetween. The loop 73 is then attached to the lower end 71 of the tape 70 and the sash balance is completely assembled.

In the mounting of the sash balance, the end 37 of the face plate or mounting plate 19 is inserted in the notch 14 below the top cross member 13 of the window frame 11 and the opposite end 33 secured thereto by inserting a fastener 36 through the hole 35. As there are two such oppositely facing sash balances 10 mounted at opposite ends of the top cross member 13, their loops 73 are connected to the upper end of the sash and the assembly is complete.

In the operation of the invention, when the sash is drawn downwardly to close the window, the tapes 70 move downwardly, rotating the drum 50 and winding up the coil springs 68, counterbalancing the weight of the sash. When the window is opened, the spring 68 unwinds, but the tendency of the window sash to descend is counteracted by the tendency of the spring 68 to wind up. The force thus generated counterbalances the sash in all its positions between its fully open and fully closed positions. Moreover, when the spring 68 is wound up during operation in this manner, a force is built up which has to be counteracted in order to hold the window in its raised position. The frictional drag set up

75 between the annular bosses 56 and 62 and the

adjacent inner surfaces of the side plates 20 and 29 provides a sufficient retarding effect to accomplish this result.

While I have shown and described my invention in detail, it is to be understood that the same is to be limited only by the appended claim, for many changes may be made without departing from the spirit and scope of my invention.

What I claim is:

A spring sash balance comprising a casing, an axle mounted in said casing, a drum mounted in said casing comprising a pair of oppositely disposed cupped cylindrical members having peripheral flanges arranged in nesting engagement and engaging said axle at axially spaced locations thereon, a spring within said drum connected at one end to said axle and at the other end to said drum, and an elongated flexible element connected to said drum and windable on the outside of the outermost flange for attachment to the sash, one of said drum members having a peripheral recess and the other drum member having a peripheral projection extend-

ing into said recess whereby to retain said members in nesting engagement.

PETER A. LUSTIG.
